UNITED STATES PATENT OFFICE.

JEAN MARIE JOSEPH ROBERT, OF PARIS, FRANCE.

DEVICE FOR HOLDING AND APPLYING MEDICAMENTS.

1,146,522.

Specification of Letters Patent. Patented July 13, 1915.

Application filed November 17, 1914. Serial No. 872,579.

To all whom it may concern:

Be it known that I, JEAN MARIE JOSEPH ROBERT, a citizen of the Republic of France, and resident of Paris, France, post-office address 37 Rue de Bourgoyne, have invented a new and useful Device for Holding and Applying Medicaments, which apparatus is fully set forth in the following specification.

10 Iodin tincture is now constantly used, and it is admitted that there is no better disinfectant for wounds, but it is difficult to carry and difficult to apply in an emergency.

15 The present invention relates to a combined vessel or bottle and brush, which facilitates the transport and the application of the contents of the vessel.

20 A construction according to this invention is illustrated by way of example in the accompanying drawing, in which—

Figure 1 is a front elevation of the brush-bottle when not in use, and Fig. 2 is an elevation showing it opened in condition for use.

25 A vessel *a* of glass or other thin, frangible material is pointed in shape and closed at both ends *b* and *c*. The vessel is constricted at *f*, which constriction separates two swollen portions *d* and *e* and is provided with a 30 circular incision or weakened line produced by a file or grinding. The two portions *d* *e* contain a wick *g* of cotton or other material. The said wick is knotted at *g'* and held in the portion *e*. A constriction *h*, 35 prevents the knotted portion of the wick from displacement. That part of the wick which forms the brush is contained in the portion *d*.

40 The whole vessel is filled with iodin tincture and when it is to be used, the part *d* by exercising a slight effort is broken away on the weakened line on the reduced portion *f*. The brush *g* then projects out of the vessel as shown in Fig. 2. When the wound 45 is being painted, iodin tincture is supplied to the wick by capillarity. If the end *b* is broken off, the wick will be impregnated more rapidly.

The vessel could be used for liquids other than iodin tincture. 50

For carrying it about, the vessel can be placed in a tube of suitable material such as metal, cardboard or bamboo.

What I claim as my invention and desire to secure by Letters Patent is:— 55

1. A device for containing and applying liquid medicaments, comprising, in combination, a tube of frangible material permanently containing the medicament in liquid form and closed at both ends, said tube having a circumferential weakened line adjacent one end; and a brush for applying the medicament having a portion thereof permanently held within said tube below said weakened line, and the remaining portion 60 normally inclosed by the last-named tube end, whereby, when the tube is broken at said line and the brush-inclosing end is removed, the brush will be exposed and the medicament will be supplied thereto by capillary attraction. 65

2. A device for containing and applying liquid medicaments, comprising, in combination, a tube of frangible material permanently containing the medicament in liquid 70 form and closed at both ends, said tube having a pair of spaced constrictions adjacent one end, the outer constriction being weakened; and a brush for applying the medicament having its inner portion permanently 75 held within said tube between the two constrictions, and its outer portion normally inclosed by the end portion of the tube beyond the weakened outer constriction, whereby when said tube is broken at said 80 weakened outer constriction and the brush-inclosing end is removed, the brush will be exposed and the medicament will be supplied thereto by capillary attraction. 85

In testimony whereof I have signed this 90 specification in the presence of two subscribing witnesses.

JEAN MARIE JOSEPH ROBERT.
